UNITED STATES PATENT OFFICE.

HARVEY A. MOYER, OF SYRACUSE, NEW YORK.

DESIGN FOR A SLEIGH.

SPECIFICATION forming part of Design No. 25,135, dated February 4, 1896.

Application filed June 26, 1895. Serial No. 554,146. Term of patent 31 years.

To all whom it may concern:

Be it known that I, HARVEY A. MOYER, of Syracuse, in the county of Onondaga, in the State of New York, have invented and produced a new and original Design for Sleighs, of which the following is a specification, reference being had to the accompanying drawing, showing a part thereof.

This design pertains to a sleigh-body, the leading feature of which design consists in the contour of the base-line of said body, the central and main portion *a* of which is curved slightly and gradually upward from the center toward opposite ends. The front portion *b* of said base-line is extended with a more abrupt upwardly-curved portion *b* and thence terminated with a forward sweep *c* of reduced curvature. The rear portion of said base-line is continued with a gradually-increasing upward curvature, as shown at *d*, terminating nearly or quite vertically and higher than the extremity of the front sweep *c*.

The top line of the body extends from the

portion *d* a short distance from the upper end thereof and in an approximately-horizontal direction toward the front, with a slightly-depressed central portion, as at *e*, and is thence curved abruptly downward, as at *f*, and continued with an approximately-vertical portion *g*, thence curved abruptly forward, as at *h*, and extended with a prolonged approximately-horizontal and slightly centrally-depressed portion *i*, terminating with a more prominently upwardly-curved portion *j* joining the base-line *a* at the junction of the portions *b c*.

What I claim as my invention is—

The design for a sleigh substantially as described and shown.

In testimony whereof I have hereunto signed my name this 24th day of June, 1895.

HARVEY A. MOYER. [L. S.]
